[57] **CLAIM**

The ornamental design for a combination water closet
and bidet, as shown.

DESCRIPTION

FIG. 1 is a perspective view taken from the front, top
and right side of a combination water closet and bidet
embodying my new design;

FIG. 2 is a perspective view taken from the front, top
and left side thereof, showing the bidet seat in its raised
position;

FIG. 3 is a front elevational view of FIG. 1;

FIG. 4 is a left side elevational view of FIG. 1; and

FIG. 5 is a rear elevational view thereof.
